(57) **CLAIM**

The ornamental design for a two-stage reflector for light, as shown and described.

DESCRIPTION

FIG. 1 is a perspective view of the two-stage reflector for light according to the present invention shown installed in a light.

FIG. 2 is a perspective view of the two-stage reflector for light according to the present invention.

FIG. 3 is a front view of the two-stage reflector for light according to the present invention. The rear view, the right side view, and the left side view are identical to the front view.

FIG. 4 is a top view of the two-stage reflector for light according to the present invention; and,

FIG. 5 is a bottom view of the two-stage reflector for light according to the present invention.

The broken lines are for illustrative purposes only and form no part of the claimed invention.
